(57) **CLAIM**

The ornamental design for daytime running light fixtures of an automobile, as shown and described.

DESCRIPTION

FIG. 1 is a front view of one embodiment a daytime running light fixture of an automobile, showing my new design;

FIG. 2 is a left side view thereof;

FIG. 3 is a rear view thereof;

FIG. 4 is a right side view thereof;

FIG. 5 is a top view thereof;

FIG. 6 is a front elevational view of the opposite side of the daytime running light fixture for an automobile showing my new design;

FIG. 7 is a left side view thereof;

FIG. 8 is a rear view thereof;

FIG. 9 is a right side view thereof;

FIG. 10 is a top view thereof;

FIG. 11 is a front view of the embodiment of FIG. 1 mounted in an automobile; and,

FIG. 12 is a front view of the embodiment of FIG. 6 mounted in an automobile.

The other parts of the automobile shown in FIGS. 11 and 12 form no part of the claimed design.
